UNITED STATES PATENT OFFICE.

JAMES J. COOPER, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

FLOOR-BEAM.

1,183,959.

Specification of Letters Patent. Patented May 23, 1916.

Application filed September 16, 1913. Serial No. 790,001.

To all whom it may concern:

Be it known that I, JAMES J. COOPER, residing at 915 Olive street, St. Louis, Missouri, and being a citizen of the United States, have invented certain new and useful Improvements in Floor-Beams, of which the following is a full, clear, and exact description, such as will enable others skilled in the art to which it appertains to make 10 and to use the same, reference being had to the accompanying drawings, which illustrate the preferred form of the invention, though it is to be understood that the invention is not limited to the exact details 15 of construction shown and described, as it is obvious that various modifications thereof will occur to persons skilled in the art.

In said drawings: Figure 1 is a plan view of a fragment of a car underframe equipped 20 with the invention herein described. Fig. 2 is a transverse vertical sectional view taken on the line 2—2 of Fig. 1, looking in the direction indicated by the arrows. Fig. 3 is a vertical longitudinal sectional view 25 taken on the line 3—3 of Fig. 2. Fig. 4 is an elevational view of a fragmentary portion of the center sill shown at the right in Figs 1 and 2, showing perforations for the transverse members which are projected 30 therethrough, as hereinafter described. Fig. 5 is an elevational view of a similar fragment of the center sill shown at the left of Figs. 1 and 2. Fig. 6 is a sectional view 35 similar to Fig. 2, showing a slightly modified form of construction and arrangement of parts, and Fig. 7 is a further modification hereinafter described.

This invention is an improvement upon the construction shown in Keithley Patent 40 707,702, and is designed to permit the use of pressed cross bearers or transoms, as they are called in said Keithley patent, which may be of any depth outside of the center sills; that is, between the center sills and side sills, 45 and which may be supported by the center sills so that the principal part of the load to be carried by the car underframe will be transmitted to the center sills, as in said Keithley patent.

To obviate cutting large openings in the center sills for the passage of continuous cross bearers through the spaced center sills is one of the objects of the invention and to permit the removal of one cantaliver portion 50 of the cross bearer of the present in-

vention without the necessary removal of the other or companion portion, is another object.

The invention is shown in the drawings as comprising a cross bearer, which derives 60 its support from the center sills and projects transversely thereof outwardly below side sills, which are mounted upon and affixed to the outer ends of the cantaliver portions of the cross bearer.

Referring specifically to the parts: A—A refer to the spaced center sill parts, which comprise vertical webs perforated, as hereinafter described, with top and bottom reinforcing angles B—C, respectively, and a 70 top cover plate D secured to the top angles B; though it is to be understood while I have illustrated a conventional form of plate girder center sill united by top cover plate, I do not wish to be limited to any 75 specific form of center sill construction, as rolled sections spaced apart or a single rolled section comprising a single center sill may be employed within the spirit of the present invention.

Cooperating with the center sill thus referred to, I employ a transverse member, which may be a cross bearer or transom intermediate the bolsters of a car underframe, or the construction may be used at and for 85 the bolster of such underframe, and where the transverse member is referred to herein it is to be understood that either a cross bearer or bolster is meant, according to the application of the particular structure desired.

The transverse member illustrated in Figs. 1 and 2 consists of two pressed diaphragms forming cantaliver supporting members comprising sections 7—7^a arranged 95 on opposite sides of the sill and opposed to each other with integral extensions 8 and 8^a, respectively, which integral extensions are framed into the vertical webs of the center sills and project therethrough to support the 100 side sills and transmit the weight of the lading directly to the center sills.

The diaphragms 7 and 7^a may be of any form outside of the center sills and may be of uniform depth from the center sills to their outer ends, or may be of increasing depth from their outer ends toward the center sills, if desired,—for example, as shown in Fig. 7. The diaphragms 7^b are deeper at 105 their inner ends; that is, the portion near 110

the center sill, than at the outer ends below the side sills, thus affording additional riveting area between the diaphragms 7^a and the center sills. Where, however, it is preferred to use diaphragms or cross bearing members which are of uniform depth outside of the center sills, I prefer to employ angle connection plates 10 of relatively large area, which are secured by rivets 11 to the webs of the center sills and by rivets 12 to the webs of said diaphragms, in addition to which I prefer to employ top and bottom tie plates 13 and 14, respectively, which tie plates pass through slots 15 and 16 cut in the webs of the center sills.

The integral extensions 8 and 8^a, shown in Fig. 2, are preferred, as relatively small openings 20 and 21 are required in the center sills with that form of construction, while the flanges 22, which partly surround integral extensions 8 and 8^a, afford a relatively large area to permit direct rivet connection of said integral extensions 8 and 8^a by means of the rivets 23, and also permit direct rivet connection of said integral extensions with the webs of the center sills by means of the rivets 24, and as the top and bottom tie plates 13 and 14 are also riveted to said integral extensions 8 and 8^a and to the extended cantaliver portions 7 and 7^a, it is evident that the cantalivers forming the transverse members are rigidly framed into the center sills.

In the modification shown in Fig. 6 the transverse member comprises the diaphragms 30—31 with integral extensions 32 and 33, each of which extensions extend through two of said spaced center sills, in consequence of which relatively shorter tie plates 13^a and 14^a may be employed, if desired, though said plates 13^a and 14^a may be continued, as shown in Fig. 2, through both center sills, the principal difference between the structure shown in Fig. 2 and Fig. 6 being that in Fig. 2 the integral extensions 8 and 8^a each pass through the web of but one sill, whereas in Fig. 6 each of the extensions 32 and 33 pass through both of the center sills, and each of the extensions 32 and 33 in Fig. 6 is riveted directly to the vertical outstanding flange of each of the angle connection plates 10, with the vertical portions of the flanges circumscribing said extensions 32 and 33 being directly riveted together by means of the rivets 35.

Secured by suitable angle connection, as 40, to the outer ends of the diaphragms 7—7^a, 30 and 31 are side sills 41, which, in

the drawings, are shown as channel sections, though it is understood that any form 60 of side sill may be substituted therefor, if desired.

What I claim is:

1. In a structure of the class described, the combination of spaced sills, a cross bearing members having lapping end portions 65 between said sills, and central tie plates extending through said sills and connected directly to said lapping portions.

2. In a device of the character described, 70 the combination of a sill, a transverse member comprising side sections, and center sections, the side sections being arranged on opposite sides of the sill and opposed to each other, and means penetrating said sills 75 and lapping the side sections and co-operating with the center sections for uniting the respective sections and maintaining said sections supported.

3. A car underframe comprising spaced 80 center sills, a transversely extending two part bearing member lapping between said sills, and a tension plate penetrating said spaced sills and connected to both parts of 85 said bearing member.

4. In a car underframe, spaced center sills each of which is perforated, a plural part cross-bearer penetrating said sills from opposite sides, top and bottom cover plates projected through said sills and lapping 90 said cross-bearer, and angle connection plates secured to the webs of said center sills and to said cross-bearer on the outer side of said sills.

5. In a car underframe, spaced perforated sills, a plural part cross-bearer the parts of which overlap intermediate said sills, angle connection plates riveted to said sills and to webs of said cross-bearer and connection plates riveted to top and bottom 100 flanges of said cross-bearer.

6. In a car underframe, spaced and perforated center sills, a plurality of flanged diaphragms having vertical webs and laterally extending flanges said diaphragms lapping intermediate said sills, connection plates secured to said sills and to said webs and a top cover plate extended through said sills and connected to the top flanges of said diaphragms beyond said sills.

In witness whereof I have hereunto set my hand in the presence of two witnesses.

JAMES J. COOPER.
